(57) **ABSTRACT**

A vehicle lamp comprises: a substrate; a semiconductor light source which is mounted on the substrate; a lens which emits light from the semiconductor light source; and a heat sink having a planar first surface which is formed in the shape of a plate from a metal material, is in contact with and affixed to the substrate, and supports the lens, and a planar second surface which is the back surface of the first surface, the heat sink being plastically deformed by a plurality of recesses disposed in a prescribed pattern in a surface machining area on the second surface that includes an area on the back side of the contact area.

1
VEHICLE LAMP

TECHNICAL FIELD

The present invention relates to a vehicular lamp.

BACKGROUND ART

A vehicular lamp to be fixed to a vehicle has a configuration including a substrate, a semiconductor light source mounted on the substrate, a lens emitting the light from the semiconductor light source in the forward direction, and a plate-like heat sink to which the substrate and the lens are fixed. In this configuration, the substrate is fixed in contact with a plate face of the heat sink. Thus, the heat generated at the semiconductor light source is transferred to the heat sink through the substrate and radiated from the heat sink. In a known method of producing a heat sink, for example, a metal member in the form of a coil is led out and then subjected to leveling and/or punching (for example, refer to PTL 1).

Patent Literature

PTL 1: Japanese Unexamined Patent Application Publication No. 2013-131388

SUMMARY OF THE INVENTION

Problems to be Solved by the Invention

However, in the production method according to PTL 1, the metal member that was in the form of a coil may have residual stress (curling) even after leveling. Thus, the heat sink may curve due to the residual stress and cause a gap to form between the heat sink and the substrate. In such a case, the transfer of heat from the substrate to the heat sink is suppressed, thereby reducing heat radiation.

An object of the present invention, which has been conceived in light of the above-described circumstances, is to provide a vehicular lamp having excellent heat radiating properties.

Means for Solving the Problem

A vehicular lamp according to the present invention, comprising: a substrate; a semiconductor light source mounted on the substrate; an optical element emitting light from the semiconductor light source; and a heat radiating element comprising a plate-like metal material, having a first flat face fixed in contact with the substrate and supporting the optical element and a second flat face disposed on the back side of the first face, and being plastically deformed by a plurality of recesses disposed in a predetermined pattern in an area on the second face including an area corresponding to the back side of the area of the first face in contact with the substrate.

The vehicular lamp according to the present invention, wherein,

the substrate is fixed to the heat radiating element with a threaded member, the heat radiating element has a screw hole penetrating the first face and the second face and receives the threaded member in the screw hole, and the recesses are disposed around the screw hole while leaving space around the screw hole.

2

The vehicular lamp according to the present invention, wherein the threaded member comprises a self-tapping screw.

The vehicular lamp according to the present invention, wherein the heat radiating element is disposed in a state with residual stress causing bending.

The vehicular lamp according to the present invention, wherein the recesses each has a polygonal shape.

10 **Effect of the Invention**

According to the present invention, a vehicular lamp having excellent heat radiating properties can be provided.

15 **BRIEF DESCRIPTION OF THE DRAWINGS**

FIG. 1 is a perspective view illustrating an example vehicular lamp according to an embodiment.

20 FIG. 2 is a perspective view illustrating an example vehicular lamp according to an embodiment.

FIG. 3 is an exploded perspective view of a vehicular lamp according to an embodiment.

FIG. 4 illustrates a configuration of a heat sink viewed from the rear.

25 FIG. 5 is a perspective view of the region A in FIG. 4.

FIG. 6 is a cross-sectional view of the configuration taken along line B-B in FIG. 4.

FIG. 7 is a perspective view of recesses according to a modification.

30 **MODE FOR CARRYING OUT THE INVENTION**

A vehicular lamp according to embodiments of the present invention will now be described with reference to the drawings. Note that the scope of the present invention should not be limited by the embodiments. The components according to the embodiments described below include those that can and readily be replaced with other components by one skilled in the art or those that are substantially the same.

35 In the descriptions below, the front-rear, up-down, and left-right directions indicate direction from the viewpoint of a driver riding in the vehicle while the vehicular front light is disposed on a surface parallel to a horizontal plane. Thus, 40 in this embodiment, the up-down direction is the vertical direction, the front-rear and left-right directions are directions parallel to a horizontal plane (horizontal directions).

45 FIGS. 1 and 2 are perspective views of an example vehicular lamp 100 according to an embodiment. FIG. 1 50 illustrates a configuration of the vehicular lamp 100 viewed from the front. FIG. 2 illustrates a configuration of the vehicular lamp 100 viewed from the rear. FIG. 3 is an exploded perspective view of the vehicular lamp 100 according to this embodiment.

55 With reference to FIGS. 1 to 3, the vehicular lamp 100 includes a substrate 10, a semiconductor light source 20, a lens (optical element) 30, and a heat sink (heat radiating element) 40. The semiconductor light source 20 is mounted on the substrate 10. The substrate 10 has a rectangular plate-like shape. The substrate 10 includes a predetermined circuit feeding electrical signals to the semiconductor light source 20, connectors connected to the circuit, and other components.

60 The substrate 10 is fixed to the heat sink 40 with threaded members 13. The threaded members 13 are, for example, self-tapping screws. Thus, the substrate 10 can be fixed to the heat sink 40 without the use of nuts and other compo-

nents. The substrate **10** is disposed in contact with the heat sink **40** via a thermal conductor, such as grease or a sheet. Thus, the substrate **10** and the heat sink **40** come into tighter contact with each other in comparison to when the substrate **10** and the heat sink **40** are in direct contact with each other, and heat transfer from the substrate **10** to the heat sink **40** is enhanced.

The semiconductor light source **20** according to this embodiment is, for example, an LED, an OEL, or an OLED (organic Els). The semiconductor light source **20** is, for example, a plurality of semiconductor light sources **20** or alternatively, a single semiconductor light source **20**. A plurality of semiconductor light sources **20** are disposed in the left-right direction at a constant pitch. Alternatively, the plurality of semiconductor light sources **20** may be disposed at any pitch besides a constant pitch. Each of the semiconductor light sources **20** has a light-emitting face. The light-emitting face, for example, faces the front of the vehicle. The semiconductor light source **20** emits light from the light-emitting face toward the front of the vehicle such that the light forms a Lambertian distribution.

The lens **30** is disposed in front of the semiconductor light source **20**. The lens **30** has an incident face and an emission face. The incident face faces the light-emitting face of the semiconductor light source **20**. The light from the semiconductor light source **20** is directly incident on the incident face. The emission face faces the front. The emission face emits the light entering the incident face to the front of the vehicle. The lens **30** is held by a lens holder **35**. The lens holder **35** holding the lens **30** is fixed to the heat sink **40** with fixing members **36**, such as screws.

The heat sink **40** is composed of, for example, a metal, such as aluminum. The heat sink **40** is formed by, for example, leading out a metal member in the form of a coil and pressing the led out metal member into a rectangular plate-like shape. The heat sink **40** is disposed such that a first face **40a** thereof faces the front and a second face **40b** thereof faces the rear.

The heat sink **40** includes a substrate fixing portion **41** and lens holding portions **42**. The substrate fixing portion **41** is disposed, for example, in the central portion of the heat sink **40** in the horizontal direction. The substrate fixing portion **41** is fixed while the first face **40a** is in contact with the substrate **10**. Thus, the first face **40a** of the substrate fixing portion **41** is provided with a contact region **47** that comes into contact with the substrate **10**. The contact region **47** is disposed in the central area of the substrate fixing portion **41** in the vertical and horizontal directions.

The substrate fixing portion **41** has screw holes **43**. The screw holes **43** penetrate the first face **40a** and the second face **40b** of the substrate fixing portion **41**. The screw holes **43** receive the threaded members **13** that fix the substrate **10**. A total of two screw holes **43** are provided at the two edges in the horizontal direction. The number and position of the screw holes **43** are not limited to those described above. For example, the number of screw holes **43** may be one or three or more, and the screw holes **43** may be disposed at any positions besides those described above.

The lens holder **35** is fixed to the lens holding portions **42**. The lens holding portions **42** hold the lens **30** by being fixed to the lens holder **35**. The lens holding portions **42** are disposed on the two sides of the substrate fixing portion **41** in the horizontal direction. In this embodiment, the heat sink **40** bends forward from the lens holding portions **42** to the substrate fixing portion **41**. The shape of the heat sink **40**, however, is not limited to this and alternatively may, for example, have a flat shape.

FIG. 4 illustrates a configuration of the heat sink **40** viewed from the rear. As illustrated in FIG. 4, the substrate fixing portion **41** has a surface treated region **44**. The surface treated region **44** is disposed on the second face **40b** in an area, for example, including the region corresponding to the back side of the contact region **47**. That is, in this embodiment, the surface treated region **44** has an area larger than the area of the back side of the contact region **47**. Note that the area of the back side of the contact region **47** is an area overlaying the contact region **47** in view of the normal direction of the second face **40b**. That is, in this embodiment, the surface treated region **44** may be disposed in an area matching the area of the back side of the contact region **47**. The surface treated region **44** has multiple recesses **45**.

FIG. 5 is a perspective view of the region **A** in FIG. 4 and illustrates example recesses **45**. As illustrated in FIG. 5, the recesses **45** each have a square pyramid shape. The length **L1** of one side of each recess **45** can, for example, be smaller than or equal to half the thickness **D** of the heat sink **40** (see FIG. 6).

The recesses **45** are disposed at a predetermined pitch **P1** in the vertical and horizontal directions of the surface treated region **44**. The pitch **P1** can, for example, be larger than or equal to twice the thickness **D** of the heat sink **40** (see FIG. 6). Note that the pitch in the vertical direction may differ from the pitch in the horizontal direction. The recesses **45** are disposed evenly across the entire surface treated region **44**.

The heat sink **40** is in a plastically deformed state by providing the recesses **45** in the surface treated region **44** of the second face **40b**. Thus, the heat sink **40** has enhanced flatness on the first face **40a** in the area of the back side of the surface treated region **44**. Note that flatness indicates the deviation from a geometrically correct flat surface of a planar body (Japanese Industrial Standards). Flatness is represented by the distance between two geometrically parallel flat planes when a planar body is disposed between the two flat planes disposed at a minimum distance (Japanese Industrial Standards).

In this embodiment, the surface treated region **44** has an area larger than the area of the contact region **47**. Thus, the entire contact region **47** has enhanced flatness. Thus, a gap does not readily form between the substrate **10** and the contact region **47** when they are in surface contact.

The heat sink **40** has a large surface area due to the recesses **45** in the second face **40b**. Thus, the surface treated region **44** having the recesses **45** has enhanced heat radiating properties.

FIG. 6 is a cross-sectional view of the configuration taken along line B-B in FIG. 4. As illustrated in FIG. 6, the recesses **45** each have a predetermined depth **D1** from the second face **40b** of the heat sink **40**. The depth **D1** of the recesses **45** from the second face **40b** of the heat sink **40** is smaller than or equal to 25% of the thickness **D** of the heat sink **40**.

Since the depth **D1** of the recesses **45** is smaller than or equal to 25% of the thickness **D**, the flatness of the first face **40a** can be enhanced without any effect on the strength of the heat sink **40**.

To produce the heat sink **40** described above, first, a metal member in the form of a coil is lead out, and then the curling of the metal member is corrected through leveling. After leveling, the metal member is pressed. Through pressing, the areas between the substrate fixing portion **41** and the lens holding portions **42** are bent, and the multiple recesses **45** are formed in the surface treated region **44** of the substrate fixing portion **41**. By forming the recesses **45**, the metal

member plastically deforms, and the flatness of the face corresponding to the first face **40a** is enhanced. Thus, for example, even when the metal member has residual stress after leveling, the flatness of the first face **40a** can be enhanced.

Then, through punching, the screw holes **43** and **46** are formed in the metal member. After forming the screw holes **43** and **46**, the metal member is cut into a predetermined shape, to provide the heat sink **40**. Note that the processing steps are not limited to the order described above. Alternatively, for example, after the metal member is leveled, the metal member may be cut and then subjected to pressing and punching.

The operation of the vehicular lamp **100** having the configuration described above will now be described. The vehicular lamp **100** emits light from the light-emitting face of the semiconductor light source **20**. The light is directly incident on the incident face of the lens **30** and is emitted from the emission face toward the front of the vehicle. The semiconductor light source **20** generates heat through emission of the light. The heat is transferred to the heat sink **40** through the substrate **10**.

In this embodiment, the adhesion of the substrate **10** and the contact region **47** is in an enhanced state. Thus, heat is smoothly transferred from the substrate **10** to the heat sink **40**. Thus, the heat generated at the semiconductor light source **20** certainly transfers from the substrate **10** to the heat sink **40** and radiates from the heat sink **40**.

As described above, the vehicular lamp **100** according to this embodiment includes a substrate **10**; a semiconductor light source **20** mounted on the substrate **10**; a lens **30** that emits the light from the semiconductor light source **20**; and a plate-like heat sink **40** composed of a metal, having a flat first face **40a** fixed in contact with the substrate **10** and supporting the lens **30** and a flat second face **40b** disposed on the back side of the first face **40a**, and being in a plastically deformed state by a plurality of recesses **45** disposed in a predetermined pattern on a surface treated region **44** of the second face **40b** including an area of the back side of a contact region **47**.

Thus, the heat sink **40** has enhanced flatness on the first face **40a** in the area of the back side of the surface treated region **44**. Thus, the adhesion of the substrate **10** and the first face **40a** is enhanced, and the conductivity of heat from the substrate **10** to the heat sink **40** is enhanced. The recesses **45** provided in the second face **40b** increase the surface area of the heat sink **40**, thereby improving the heat radiating properties. In this way, a vehicular lamp **100** having improved heat radiating properties is obtained.

In the vehicular lamp **100** according to this embodiment, the substrate **10** is fixed to the heat sink **40**; the heat sink **40** has the screw holes **43** penetrating the first face **40a** and the second face **40b** and receiving the threaded members **13**; and the recesses **45** are disposed around the screw holes **43** while leaving space around the screw holes **43**. In this way, the screw holes **43** are prevented from deforming, and thus, the threaded members **13** can be certainly inserted into the screw holes **43**, to certainly fix the substrate **10**.

In the vehicular lamp **100** according to this embodiment, the threaded members **13** are self-tapping screws. In this way, the substrate **10** can be fixed to the heat sink **40** without providing nuts or other components on the second face **40b**. If nuts are to be provided on the second face **40b**, the multiple recesses **45** should be disposed in areas avoiding the nuts. Thus, by omitting the nuts or other components, the recesses **45** can be disposed in a large area on the second face **40b**.

In the vehicular lamp **100** according to this embodiment, even when the heat sink **40** has residual stress and is in a state of bending, the heat sink **40** is in a plastically deformed state by the multiple recesses **45**. Thus, the flatness of the first face **40a** in the area on the back side of the surface treated region **44** can be enhanced.

In the vehicular lamp **100** according to this embodiment, the surface treated region **44** is disposed in an area larger than the area of the back side of the contact region **47**, and thus the heat transferred from the substrate **10** to the heat sink **40** can be readily radiated from the second face **40b**. In this way, a vehicular lamp **100** having improved heat radiating properties is obtained.

Furthermore, in the vehicular lamp **100** according to this embodiment, the recesses **45** each have a polygonal shape, thereby readily causing plastic deformation of the heat sink **40**. In this way, a vehicular lamp **100** having improved heat radiating properties can be readily produced.

Although the present invention has been described on the basis of specific embodiments, the present invention is not limited to above embodiments. For example, in an embodiment described above, the recesses **45** each have a square shape. The shape of the recesses **45** is not limited thereto, and may be any other polygonal shape. Note that the shape of the recesses **45** is not limited to a polygon and alternatively may be a semi-circular shape, a conic shape, or any other shape.

FIG. 7 is a perspective view of recesses **45A** according to a modification. As illustrated in FIG. 7, the recesses **45A** may each have a regular tetrahedral shape. The length **L2** of one side of each recesses **45A** can, for example, be smaller than or equal to half the thickness **D** of the heat sink **40** (see FIG. 6).

The recesses **45A** are disposed at a predetermined pitch **P2** in the vertical and horizontal directions. The pitch **P2** can, for example, be larger than or equal to twice the thickness **D** of the heat sink **40** (see FIG. 6). In such a case, the pitch in the vertical direction may differ from the pitch in the horizontal direction. The recesses **45A** are disposed evenly across the entire surface treated region **44A**. In this way, the flatness is adjusted to be uniform in the entire area of the first face **40a** corresponding to the surface treated region **44A**.

In the embodiments described above, the vehicular lamp **100** has a direct-irradiation type configuration in which the lens **30** is provided as an optical element, and the light from the semiconductor light source **20** is directly incident on the lens **30**. However, the configuration is not limited thereto. For example, the vehicular lamp **100** may have a configuration (multi-reflector type, projector type, etc.) in which a reflector replaces the lens **30** as an optical element, or a combination of the lens **30** and the reflector is used as an optical element, and the light distribution pattern is formed by light from the semiconductor light source **20** reflected forward at the reflective face of the reflector.

DESCRIPTION OF REFERENCE NUMERALS

- A region
- P1, P2 pitch
- 10 substrate
- 13 threaded member
- 20 semiconductor light source
- 30 lens
- 35 lens holder
- 36 fixing member
- 40 heat sink
- 40a first face

- 40b second face
- 41 substrate fixing portion
- 42 lens holding portion
- 43, 46 screw hole
- 44, 44A surface treated region
- 45, 45A recess
- 47 contact region
- 100 vehicular lamp

The invention claimed is:

1. A vehicular lamp comprising:
  - a substrate;
  - a semiconductor light source mounted on the substrate;
  - an optical element emitting light from the semiconductor light source; and
  - a heat radiating element composed of a plate-like metal member and having a first flat face fixing the substrate which is in contact therewith and supporting the optical element and a second flat face disposed on the back side of the first face, wherein a plurality of recesses are provided in a predetermined pattern in at least an area

on the second face which is the back side of the area of the first face corresponding to the substrate, wherein the plurality of recesses are provided by plastic deformation of the plate-like member.

- 5 2. The vehicular lamp according to claim 1, wherein, the substrate is fixed to the heat radiating element with a threaded member,
- 10 the heat radiating element has a screw hole penetrating the first face and the second face and receives the threaded member in the screw hole, and
- 15 the plurality of recesses are disposed around the screw hole while leaving space around the screw hole.
3. The vehicular lamp according to claim 2, wherein the threaded member comprises a self-tapping screw.
4. The vehicular lamp according to claim 1, wherein the heat radiating element is disposed in a state with residual stress causing bending.
5. The vehicular lamp according to claim 1, wherein the plurality of recesses each has a polygonal shape.
